UNITED STATES PATENT OFFICE

165,368

FOUNTAIN BRUSH

Anders H. Flater and Roald H. Flater, Evanston,
Ill., assignors to Anro Products Company, Inc.,
Chicago, Ill., a corporation of Illinois

Application March 28, 1951, Serial No. 14,650

Term of patent 3½ years

(Cl. D9—2)

To all whom it may concern:

Be it known that we, Anders H. Flater and Roald H. Flater, citizens of the United States, residing at Evanston, State of Illinois, have invented a new, original, and ornamental Design for Fountain Brush, of which the following is a specification, reference being had to the accompanying drawing, forming a part hereof, wherein,

Fig. 1 is a side elevational view of a fountain brush embodying our new design; and

Figs. 2 and 3 are reduced perspective views of the brush, respectively showing bottom and top aspects of the same.

We claim:

The ornamental design for a fountain brush, as shown.

ANDERS H. FLATER.
ROALD H. FLATER.
